UNITED STATES PATENT OFFICE

1,939,800

DISPLAY REFRIGERATOR

Virgil P. Warren, Atlanta, Ga.

Application July 9, 1932. Serial No. 621,700

3 Claims. (Cl. 62—37.1)

This invention relates to display refrigerators and proposes an improvement in refrigerators of the showcase type employing ice and brine as the refrigerant.

One of the objects of the invention is to provide a display refrigerator which in its novel construction obviates the use of the customary side ice bunkers, and substitutes instead an ice tank, centrally arranged within the showcase 10 in the upper part thereof, and preferably extending throughout the length of the refrigerated chamber.

By this arrangement a natural convection circulation of air is set up and maintained, the 15 cold air descending in the center toward the bottom of the case and the warmer air arising adjacent the walls of the showcase, minimizing the rate of heat exchange with the outer atmosphere, and thus enhancing the efficiency of the 20 showcase, the absence of side bunkers permitting the display space to extend throughout the entire length of the showcase.

Another object of the invention is the provision of the refrigerating tank in a focal position, to produce the efficient air circulation above referred to, said tank being adapted to be charged with broken ice and salt and constructed so as to cause the relatively warm air to flow 25 through the interstitial spaces between the ice 30 lumps, and in contact with the ice, whereby the air is cooled, humidified and filtered, and descends through a longitudinal opening at the bottom of the tank, the air in the filtering being cleansed of undesirable food flavors, and re- 35 turned to the refrigerated chamber in optimum condition as regards low temperature and high humidity.

A further object of the invention is the provision of means for automatically preventing 40 frost condensation on the outer surfaces of the ice tank, whereby through the avoidance of ice insulation, the refrigerating efficiency of the ice tank is further improved.

Still another object of the invention is the 45 efficient utilization of the liquid brine discharge from the brine tank in the further cooling of the refrigerated chamber.

Another object of the invention is the provision 50 of a refrigerated showcase of universal construction to the extent that it may be converted into an efficient mechanical refrigerator, simply removing the reticulated partition and installing a mechanical coil within the ice tank.

55 Other objects of the invention will appear

as the following description of a preferred and practical embodiment thereof proceeds.

In the drawings which accompany and form a part of the following specification and throughout the several figures of which, the 60 same characters of reference have been employed to designate identical parts:

Figure 1 is a perspective view of a refrigerated showcase embodying the features of the present invention; 65

Figure 2 is a vertical cross section of the same;

Figure 3 is a cross section through the ice tank;

Figure 4 is a perspective view of a portion of the ice tank; 70

Figure 5 is a vertical section taken along the line 5—5 of Figure 3;

Figures 6 and 7 are detailed views in perspective of braces used to support and retain the shape of the screen baffle which extends 75 longitudinally along the middle of the ice tank;

Figure 8 is a perspective view showing in detail, one end of the drip trough;

Figure 9 is a horizontal section through a portion of the showcase showing means for dehydrating the cells between the spaced panels; 80

Figure 10 is a vertical section showing the same;

Figure 11 is a horizontal section through the selective dehydrating valve; and 85

Figure 12 is a section taken along the line 12—12 of Figure 11.

Referring now in detail to the several figures, the numeral 1 represents in general the showcase comprising the usual side, top and back 90 walls and the front display window 2, which as shown in Figure 9, is for purposes of improved heat insulation, formed of a plurality of glass panels 3, set into suitable framework, represented by elements 4 and 5 and defining with 95 said framework air cells 6 and 7. The back wall of the case is provided with suitable doors 8, giving access to the refrigerated chamber and the top is preferably formed as a hinged lid 9 to facilitate icing. 100

Within the showcase arranged adjacent the top portion thereof is the ice tank 10 which preferably extends throughout the length of the showcase. It will be observed from Figure 1 that due to the absence of the side ice bunkers which were indispensable to the older type of refrigerated showcases, the display space occupies substantially the entire length of the showcase. 105

An intermediate shelf 11 is shown and a shelf 12 at the bottom of the showcase, but it is to be 110

understood that the location of these shelves is optional and that one or both may be omitted if desired.

In the well known side bunker type of refrigerated showcase, it was customary to charge the bunkers with a mixture of ice and salt, thereby producing a cold atmosphere in the bunkers which was compelled to travel laterally toward the middle of the showcase in order to refrigerate the same properly. Since a lateral, that is to say, a horizontal flow of cold air is not in a natural convection direction, it is obvious that this flow was either very sluggish or else had to be induced by mechanical means such as a blower. By arranging the ice and salt tank in the top of the refrigerated chamber, the cold air eventuating therefrom descends naturally downward along the middle of the case, and the displaced warmer air ascends along the walls of the showcase.

Referring to Figures 3 and 4, it will be noted that the ice tank is provided with a median slot 13 extending longitudinally along its bottom and that from the sides of said slot a wire screen baffle 14 arises, preferably substantially to the height of the tank. Said screen baffle is preferably formed by folding a piece of wire screen into an inverted V-shape, and it may be secured by flanging the bottom edges thereof as is indicated by 15 and securing the flanged portions under strips 16, the latter being securely bolted to the bottom of the tank. The screen baffle is supported at the ends of the tank by a bent metallic brace 17 shown in Figure 6, and at intermediate points it is supported by the rigid spacers 18.

It will be understood that the details of construction of the brace 17 and spacers 18 are matters of but little moment to the present invention, and that numerous equivalent variations in the form of these elements may be made without transcending the scope of the invention.

The ice tank 10 is designed to be charged with lumps of ice on both sides of the baffle 14, interspersed with sufficient salt to produce the desired refrigerating temperature. Figure 2 shows that the ice tank is supported in spaced relation as indicated by the reference character 19 from the top of the refrigerated chamber and that it is spaced from the side walls of the showcase providing a path for the circulation of air upward along the front and back of the showcase down into the ice tank, through the interstices in the ice, through the screen baffle 14 and out through the slot 15.

Since said slot is above the middle of the refrigerated chamber, the cold air flows downward to the bottom of the refrigerator in the center thereof and in cooling relation to the underlying shelves 11 and 12. By virtue of the dropping of the cold air through the center of the tank to the bottom of the case, the warmer air comes in contact with the glass panels and with the walls of the case, this being particularly important with relation to the temperature at the bottom of the case, as with ordinary refrigeration, the bottom is subjected to the most extreme cold while in the present invention the circulation of the air has the tendency to return by way of the side walls to the top of the case, again filtering through the ice and down the center of the case.

By having the warmer currents flow against the glass and side walls, there is a smaller temperature differential between the air inside and

that outside of the case and therefore, there is a less heat transfer so that the desired temperature of the refrigerating chamber can be produced and maintained with a much higher temperature of the refrigerating medium. This offers a considerable saving in ice and allows an extremely high efficiency in the melting of the ice and also effects economy in the use of salt since a much less quantity of salt is required to produce the low temperature which is found sufficient to produce the desired temperature, than was possible in the older types of refrigerator, in which a lower temperature of the ice tank had to be maintained.

A drip trough 20 is arranged beneath the slot 15 and catches the brine resulting from the melting of the ice and the dissolving of the salt. The bottom of the drip trough slopes as indicated at 21 in Figure 5. At the lower end is a drain pipe 22 which discharges into a brine settling basin 23 of some capacity, having a baffle 24 extending downwardly and terminating adjacent the bottom of said basin. The drain pipe 22 discharges on one side of this baffle and on the other side is an overflow pipe 25 extending to a point near the top of the settling basin. Thus the brine is compelled to flow beneath the baffle 24, all floatable matters coming to the surface and matters which will not float collecting in the bottom of the settling basin. The overflow pipe leads into the anterior end 26 of a coil 27, the limbs of which are preferably arranged in labyrinthine manner adjacent to the shelf 11. A discharge pipe 28 arranged in the form of a trap is connected to the posterior end of the coil 27 and is so determined that the effluent brine is no colder than the refrigerator temperature.

The drip trough is made sufficiently wide to catch any dew which may condense on the outer wall of the ice tank and which may flow down the depending flanges 36 formed at the lower edges of the bottom wall of the tank and which overlie the said drip trough. In order to prevent condensed moisture from the drip trough being precipitated upon the foodstuffs on the shelves below, a trough shaped baffle 37 is provided, underlying the drip trough and inclined slightly toward the settling basin 23 into which it drains. This baffle is preferably supported in spaced relation to the drip trough by means of angle bars 38, fixed to the underside of the drip trough and extending longitudinally, and short spacing blocks 39, preferably of wood or other insulating material. Free circulation of air between the drip trough and baffle, together with insulated relation of these two elements, maintains a temperature differential between them that keeps the temperature of the baffle above dew point.

For the prevention of frost accumulation upon the outside of the ice tank, with the attendant annoyance of its melting and dripping upon the foodstuffs, the ice tank is made double walled, the walls being constituted by two metal sheets 30 and 31 spaced apart at intervals by short blocks 32 of wood or other suitable insulation material, forming a jacket which communicates along its lower edge with the air eduction slot 15. The ends of the jacket thus formed are closed by the abutment of the ice tank against the end walls of the showcase or by suitable filler pieces not shown. The top edges of said jacket are closed and supported by continuous longitudinal wooden stringers 33. In order to assure the substantial absence of thermal con-

ductivity between the inner and outer walls of the ice tank, the stringers 33 and the blocks 32 are secured in place as shown in Figure 3 by bolts 34, the heads of which are countersunk, 5 as shown at 35, so as to be out of contact with one of the walls, the bolt passing through and securing the other wall in place.

The low temperature produced by the ice and salt in the ice tank reduces the temperature of 10 the air in the jacket between the walls 30 and 31, densifying said air and therefore, increasing its weight so that by convection it tends to descend and spill out of the lower longitudinal open end of the jacket. This produces a partial vacuum 15 within the jacket providing sufficient insulation to maintain high enough temperature on the outside casing to prevent ice and frost formation.

Means are provided to prevent moisture condensation on the multiple panes of the glass 20 panel 3. This means is the same as forms the subject matter of my Patent No. 1,856,008, granted April 26, 1932, and comprises a casing 43, attached at any convenient point and preferably to one side of the showcase, said casing 25 containing a dehydrating chemical such for example as calcium chloride. Said casing is connected, through selectively operable distributing valves 44, with air circulating conduits 45 and 46, each of which includes one of the window 30 spaces in its circuit.

A blower 47 intercalated in the common limb 48 of the circulating conduits produces air circulation through the drier and though either or both of the window spaces, drying the air 35 and thereby preventing condensation of moisture or frost on the window panes. The blower may be operated periodically when required.

In view of the scientific coordination of the 40 various features of this invention, and the consequent high thermal efficiency thereof, it is possible to maintain a showcase atmosphere as low as 20° F. or lower, with a variation of not more than 3 or 4° in the temperature at the top and bottom of the case, with a minimum 45 quota of salt and a surprisingly low ice meltage.

It is, of course, understood that the specific 50 details of construction as illustrated and described are merely exemplary of a preferred embodiment of the invention and not as limiting the scope of the invention as claimed.

What I claim is:

1. Refrigerator comprising walls forming a

chamber, an ice tank extending longitudinally in the upper part of said chamber having an air eduction slot in its bottom remote from said walls, a screen partition upstanding in said tank and bridging said slot, a drain trough beneath said slot, said tank being arranged in a focal position to determine an air circulation upward adjacent said walls, over and through the ice in the ice tank through said screen partition, and down through said eduction opening, 80 said drain trough spanning the width of said eduction opening and functioning as a baffle to divide the downward air circulation, in effect increasing the width of the air current, a settling basin into which said trough discharges, 85 and a coil receiving the discharge from said settling basin and conducting it circuitously in a substantially transverse plane through said chamber.

2. Refrigerator comprising walls forming a 95 chamber, an ice tank extending longitudinally in the upper part of said chamber having an air eduction slot in its bottom remote from the walls of said chamber, said ice tank being arranged in a focal position to determine an air 100 circulation upward adjacent said walls, over and through the ice in the ice tank, and down through said eduction slot, said ice tank being double walled for the avoidance of frost on the outer surface thereof, the space between the 105 walls of said ice tank being isolated from said chamber except at the bottom where said space opens in the path of the descending air circulation adjacent said eduction slot, for maintaining an insulating partial vacuum within said 110 space induced by the gravitational descent of the dense air within said space and its entrainment in the descending air circulation.

3. Refrigerator comprising walls forming a 115 chamber, an ice tank in said chamber having an air eduction opening in its bottom, remote from the walls of said chamber, said ice tank being double walled for the avoidance of frost on the outer surface thereof, the space between the 120 walls of said ice tank being isolated from said chamber except at the bottom, for maintaining an insulating partial vacuum within said space induced by the gravitational descent of the dense air within said space, entrained in the downward current of air passing through 125 said eduction opening.
